DRESSER OR THE LIKE

Ernest Herrmann, Hillsdale, N. J., assignor to Heywood-Wakefield Company, Gardner, Mass., a corporation of Massachusetts

Application December 14, 1954, Serial No. 33,560

Term of patent 7 years

(Cl. D33—6)

Fig. 1 is a front perspective view of a dresser or the like showing my new design.

Fig. 2 is a fragmentary sectional view on the line 2—2 of Fig. 1,

Fig. 3 is an enlarged fragmentary view along the line 3—3 of Fig. 1, partly in section and partly in perspective,

Fig. 4 is an enlarged perspective view of one of the elongated handle elements.

The stippling on the elongated handle elements indicates contrast.

The dominant features of the design reside in the portions shown in full lines.

I claim:

The ornamental design for a dresser or the like, substantially as shown and described.
